DESIGN FOR A VEHICLE TIRE

Elue O. Fritch, Cumberland, Md., assignor to The
Kelly-Springfield Tire Company, Cumberland,
Md., a corporation of New Jersey

Application February 16, 1934, Serial No. 50,748

Term of patent 14 years

To all whom it may concern:

Be it known that I, ELUE O. FRITCH, a citizen of the United States, residing at Cumberland, in the county of Allegany and State of Maryland, have invented a new, original, and ornamental Design for a Vehicle Tire, of which the following is a specification, reference being had to the accompanying drawing, forming a part hereof.

Figure 1 is a perspective view of a tire embodying the new design,

Figure 2 is a vertical cross-section taken on line 2—2 of Figure 1.

Figure 3 is an enlarged fragmentary view in side elevation of a portion of the new design.

I claim:

The ornamental design for a vehicle tire as shown.

ELUE O. FRITCH.
